CLAIM

The ornamental design for a range hood for modular housing, as shown and described.

DESCRIPTION

FIG. 1 is a bottom front perspective view of a range hood for modular housing, showing our new design;

FIG. 2 is a top plan view thereof;

FIG. 3 is a front elevation view thereof;

FIG. 4 is a right side elevation view thereof;

FIG. 5 is a left side elevation view thereof;

FIG. 6 is a bottom plan view thereof;

FIG. 7 is a rear elevation view thereof;

FIG. 8 is a top plan view of a range hood for modular housing, showing a second embodiment of our new design;

FIG. 9 is a rear elevation view of FIG. 8; and

FIG. 10 is a top plan view of a range hood for modular housing, showing a third embodiment of our new design.

The bottom, front, and sides of the second and third embodiments and rear of the third embodiment of the range hood are understood to be the same as the bottom, front, and sides of the first embodiment and rear of the first embodiment of the range hood as shown in FIGS. 2, 3, 4, 5 and 7 respectively.

FIG. 1.

FIG. 2.

FIG. 3.

Fig. 4.

Fig. 5.

Fig. 6

Fig. 7.

FIG.8.

FIG.9.

FIG. 10.
